FUSE

Nathaniel N. Okun, Bronx, N. Y.

Application June 13, 1930. Serial No. 460,843

3 Claims. (Cl. 200—131)

This invention relates to fuses for electric light circuits and is herein disclosed as embodied in a familiar type wherein the fusible link lies in a fiber tube having metal caps on 5 the ends.

In such fuses the link is replaceable, and when an electrician removes the fuse from the circuit the electrician often receives an electric shock, sometimes because there is no convenient place 10 to seize the fuse and sometimes because the poor connection between the link and the end terminals has caused an arc to form and burn away part of the fiber tube with the result that the metal parts slip and touch the fingers 15 of the electrician giving him a shock.

According to the present invention these and other difficulties are overcome in either of two ways or in both ways. One form of the invention provides an improved form of fiber tube or 20 grip which removes all temptation from the electrician to seize the tube elsewhere, and yet is so formed as to conform to the rules of the fire underwriters.

The other or additional form of the invention provides an improved connection or improved seizing surfaces at the terminals to enable them to surely hold the fusible link, and yet be readily connected to it. These connections 25 may vary with the type of link, which varies 30 with the load of current the fuses are adapted to carry.

Other features and advantages will herein-after appear.

In the accompanying drawings:

35 Figure 1 is a top view of a fuse embodying the present invention and adapted to carry up to thirty amperes of current.

Figure 2 is an end view of the same with the fuse in place.

40 Figure 3 is a similar view showing the link inserted and the parts before the link is made fast.

Figure 4 is an enlarged section 4—4 of Figure 2.

45 Figure 5 is a perspective showing the link being inserted.

Figure 6 is a view of the modified structure used in a fuse for carrying a heavier current—up to 60 amperes, parts being broken away.

50 Figure 7 is an end view of the same.

Figure 8 is a section on the line 8—8 of Figure 7.

Figure 9 is a face view of the fusible link.

55 Figure 10 is a face view of the parts which hold the link before inserting the link.

Figure 11 is a perspective view of a fuse adapted to carry still heavier currents.

Figure 12 is a left end view of the parts seen in Figure 11.

Figure 13 is a view of the same parts showing how the fusible link is held.

Figure 14 is a sectional view of one end of Figure 11 taken on the line 14—14 of Figure 12.

Figure 15 is a face view of the fusible link.

The fuse of Figure 1 includes any desired or 65 usual tubular fiber casing 20 having end pieces 21 of metal which may be identical and be held to the casing in any desired manner as by screws 22.

To enable any one to safely replace one fuse 70 by another, or to hold the fuse for inserting or removing it, the casing 20 is provided with a finger grip 23 which may be midway of the casing and only thick enough to provide sufficient strength, thus it is thinner than the casing 20, 75 and can be inserted any where that the casing may be inserted as part of the fuse. The grip 23 may be about half or less the length of the casing between its metal ends 21, and may be molded as part of the casing 20 or suitably made 80 fast thereto. It is preferably made of insulating material, and for sureness of grip is hollowed out, as at 24, on each face so that it fits any normal thumb and forefinger.

The fusible link 25 is made long enough to 85 project at each end through an opening or slot 26 in a rotatable holding member 27 held by a screw 28 to the end or cover piece 29 of a metal end 21, said screw entering a threaded central opening 30 of the member 27. The slot 26 enters at edge of the member 27 and runs far enough across the member 27 to easily accommodate the link 25.

The member 27 is shown as cut away at 31, at the end of the slot nearest the screw hole 30, 95 thus providing an opening through which the end of the link 25 may be inserted, instead of requiring that it be inserted into the slot itself. When thus inserted the end of the link 25 may also project through an opening made by cutting 100 away the cover piece 29 at 33 so that it just leaves a clear opening to the slot 26.

When a link 25 is thus inserted, the electrician turns the screw 28 to draw the member 27 against the under side of the cover piece 29, and in so doing rotates the member, carrying the end 34 of the fusible link 25 under the cover piece 29 so that it is bent over and slides along the under surface of the cover piece 29 forming a clean electrical contact therewith. 110

To limit the throw or turn of the rotatable holding member 27 it is provided with a lug 35 which projects radially through a cut 36 in the periphery of the end 21.

5 The lug lies almost against the end 37 of the cut 36 in inserting the link 25 in the slot 26, thus positioning the slot 26, and, if need be, serving as a finger piece for turning the member 27 to position the slot 26.

10 Upon turning the screw 28 the member 27 turns until the lug 35 strikes against the opposite end of the cut 36, and this end is usually further around than the edge 33, with the result that the member 27 adjacent the lug 35 lies largely under the cover piece 29 when the screw 28 is tight. The lug finally lies in the center plane of the finger grip 23.

15 Both ends of the fuse may be provided with identical parts, and the screws 28 may be provided with suitable devices as upset ends 39 so 20 they can not be unscrewed and become loose and thus lost.

20 The fuse of Figure 6 is provided with a slightly modified form of ends 40 on its fiber casing 20 which may have the finger grip. The fusible link 25, in this form of the invention, is adapted to project through a slot 41 with closed ends and nearly in the center of the cover piece 42. The link is provided with forked ends 47 adapted, 25 as they project through the slot 41, to be bent down around the stem 43 of a screw 44 by rotating a cover disk 45 around a pivot 46 near one edge of the cover piece 42. As the cover disk 45 swings around its pivot, it cams the projecting ends 47 down on to the upper surface of the cover piece 42.

25 The cover disk 45 is provided with a slot 48 adapted to admit the stem 43 of the screw 44 and just long enough to allow the disk 45 to 30 swing until it coincides with the cover piece 42. In that position the ends 47 of the link 25 have been cammed down flat and scraped clean. The screw 44 is then tightened and the fuse is ready 35 for use. It should be noted that tightening of the screw 44 causes its head 49 to turn on the disk 45 outside the slot so as to tend to draw the end of the slot 48 against its stem 43.

40 In Figure 11 is shown the fuse for heavy electric currents provided with an analogous case

45 20, which may also have a finger grip. Its metal end 50 is shown as carrying a contact lug 51 fast to or integral with it, as desired. The link 25 is shown as projecting through an almost radial slot 52 in the cover piece 53, so 50 that the forked ends 47 may be bent down to lie on opposite sides of the stem 54 of a screw 55 threaded into the cover piece 53.

55 When thus bent, or partly bent down, a swinging segment member 56 pivoted on a rivet at 57 near one edge of the cover piece 53 is swung over the forked ends 47 to cam them flat so that a slot 58 in it embraces the stem 55 and its flat edge 59 lies against the base of the contact lug 51. Then the screw 55 is tightened down 60 on the segment 56, the parts being so arranged that the tightening of the screw tends to throw the segment against the lug 51.

65 Having thus described certain embodiments of the invention what I claim is:

70 1. In a fuse having a body, the combination with a fusible link, of a pair of relatively rotatable members, a slot in the rotatable member so located that the link projecting through the slot projects past a cutaway portion of the other member, and a screw threaded into the other member adapted to draw the members together and in so doing tending to draw the link under the body of the other member.

75 2. In a fuse having a hollow non-conducting body, the combination with a fusible link and a first end member having a slot through which an end of the link projects, of a second end member, the second end member having an eccentric edge and being rotatable on the other 80 to bend over the projecting end of the link by the edge, and a screw passing through one of the members to draw the other against it.

85 3. In a fuse having a hollow non-conducting body, the combination with a fusible link and a first end member having a slot through which an end member having an eccentric edge and being rotatable on the other to bend over the projecting end of the link by the edge, and a screw passing through one of the members to 90 draw the other against it and adapted to tend to continue turning the rotatable member in the same direction.

NATHANIEL N. OKUN.
